3 Sheets-Sheet 3

UNITED STATES PATENT OFFICE.

HEINRICH BOCKISCH, DECEASED, LATE OF POUGHKEEPSIE, NEW YORK; BY GEORGE W. GITTINS, ADMINISTRATOR, OF NEW YORK, N. Y., ASSIGNOR TO WELTE-MIGNON CORPORATION, OF NEW YORK, N. Y., A CORPORATION OF NEW YORK.

STARTING DEVICE FOR SYNCHRONIZERS.

Application filed April 21, 1920. Serial No. 375,579.

To all whom it may concern:

Be it known that HEINRICH BOCKISCH, deceased, late a citizen of the Republic of Czechoslovakia, and formerly residing at

6 Poughkeepsie, in the county of Dutchess and State of New York, United States of America, invented certain new and useful Improvements in Starting Devices for Synchronizers, of which the following is a specification.

10 This invention relates to automatic musical instruments and particularly to that type of apparatus for maintaining two musical instruments in synchronism musically.

15 The object of this invention is the provision of means co-ordinating the starting of two instruments for example an automatic musical instrument and a phonograph so that both instruments will start at the same 20 time, thus enabling the synchronizer to function properly at the start of the musical selection.

It consists broadly in the provision of a single starting means for the two instruments 25 so constructed that the two instruments will be placed in full operation at the same time.

My invention is well adapted for use with, and has been illustrated in connection with 30 parts of, the synchronizer shown and described in the patent to H. Bockisch, 1,279,640, September 24, 1918. It is however of broader application than for use with the particular synchronizer of the said patent 35 and may be used with other synchronizers making necessary only such changes as might be made within the skill of a mechanic in the art.

Referring to the drawings:

40 Figure 1 is a diagrammatic drawing of the elements of my invention showing the electrical connections to the synchronizer such as is shown in the patent to H. Bockisch, 1,279,640, September 24, 1918.

45 Figure 2 is a fragmental perspective view of the phonograph table showing the starting and stopping lever and the electrical connections thereto.

Figure 3 is a plan view of the block carrying the contact for the starting connections for the devices to be synchronized.

50 Figure 4 is a perspective view of the block.

Figure 5 shows the lever carrying contact

when in its different positions relative to 55 the block for starting (left), running (middle) and stopping (right).

Figure 6 is a perspective view of the winding and rewinding gear mechanisms of the 60 automatic musical instrument.

Like reference characters refer to similar parts in the several views.

Referring to the figures of the drawings, 10 designates the tracker box of an automatic musical instrument and 11 the shaft connected with the take-up roll. 12 designates the shaft which carries the music spool. A small gear 12' is mounted on the shaft 12, and meshes with the rewind idler gear 14. 13 designates the winding gear. 15 70 designates a small gear which is mounted on the shaft 16 which latter is connected to the motor. The shaft 16 is mounted on a lever 17 pivoted at the point 18. The shaft 16 is provided with suitable universal 75 joints to enable the lever 17 to swing without disturbing the connections. The lever 17 is capable of swinging so as to engage either the take-up gear 13 or the rewind idler 14. 80

I will now describe the mechanism used to start the driving mechanism for the automatic musical instrument. When the magnet 18 is energized, it lifts its armature 19 which carries a valve 20 for controlling the 85 admission of air to the duct 21. Under normal conditions with the duct 21 closed, the chambers 22 and 23, which are separated by the diaphragm 24, are under tension. The chamber 23 is connected to an air pump which maintains a tension in the chamber 23. The chambers 23 and 24 are connected by a bleed 25. During the time the duct 21 is closed by the valve 20 the bleed 25 maintains tension below the diaphragm so that 90 the pressure in the two chambers is equalized. When however the valve 20 is raised, air at atmospheric pressure enters the duct 21, destroys the partial vacuum below the diaphragm 24 raising the same. This causes 95

the valve stem 26 to raise the valve 27, cutting off the atmospheric port 28 and opening the exhaust port 29 and thus connecting the chamber 23 with the bellows 30. This collapses the bellows 30 forcing down 100 the rod 31 pressing on the lever 17 through the nut 32. This tilting of the lever 17 places the gear 15 which is being revolved 105

by the motor, in mesh with the gear 13 to wind the sheet from the music roll on the shaft 12.

The phonograph table 32 is started by the 5 starting handle 33 which carries a pad 34 having a contact with the rim 35 of the table 32. When the starting handle 33 is moved to the left as shown in Figure 2, it releases the pad 34 from the rim 35 in the usual 10 manner and the phonograph table starts rotating.

Beneath the table 32 of the phonograph is an arcuate control contact member 36 which is in the circuit of the synchronizer 15 and acts as a circuit closing member in connection with other parts of the synchronizer to control the relative speed of the phonograph record and music sheet.

Adjacent the phonograph table and not 20 revoluble therewith are the two yielding contact elements 41 and 42 which correspond respectively to the contacts 11 and 12 of the aforesaid patent. In this invention the wire from the contact 41, instead of going 25 straight to the battery as in the case of the circuit in the patent, leads first to a contact member 43 on the block 44. Connected to the starting handle 33 and in position to engage the contact member 43 is a circuit 30 closing member 45 which is connected by its mounting to the battery. Mounted also on the block 44 is a contact member 46 in position also to be engaged by the circuit closing member 45 and having an insulating member arranged therebeneath and being designated 35 55.

The contact element 42 leads to the terminal 102 by the wire 101 of the synchronizer as in the case of the patent.

40 Power is derived for the operation of the synchronizer and starting device from a battery N, its positive side being connected to the terminal 113 by the wire 112 and its negative terminal being connected to the 45 terminal 110 by the wire 111. In order to make the operation of this device clear without showing and describing the whole synchronizer, I have indicated the synchronizer on Figure 1 and illustrated and designated 50 the lugs necessary to connect this invention to the synchronizer shown in the hereinbefore mentioned patent.

On the side of the tracker box 10 and adjacent the lever 17 is a spring held lever 47 55 having a projection 48 in position to engage a notch 48^a in the end of the lever 17. The spring 49 normally holds the projection 48 in registry with the notch 48^a. However, when the rod 31 through the nut 32 forces 60 the rear lever 17 downward, the same is held in this position by the projection 48 until released by mechanism to be later described.

The sheet 50 is shown diagrammatically in Figure 1 passing over the tracker bar 51.

65 At the edge of the sheet are control perfora-

tions 52 which correspond to the control member 36 of the phonograph. When the two instruments are in perfect synchronism one perforation 52 passes over the tracker duct 53 during the time that the arcuate control member is in contact with the contact members 41 and 42. 70

The sheet and tracker mechanism are provided with cooperating mechanism whereby when the sheet has been fully played, the 75 gear 15 will be put in mesh with the gear 14 and the roll rewound after which the gear 15 is returned to the position shown in Figure 1. This mechanism is, however, no part 80 of this invention and is merely indicated at 54.

I will now describe the operation of my invention as applied to a synchronizer for two automatic musical instruments one of 85 which is a phonograph.

The phonograph record is placed on the phonograph table having its starting mark at the indicated plate (not shown) on the table and the needle in its proper place ready to play. The phonograph table is 90 turned until the brushes are about to leave the arcuate contact member on the table. The note sheet or perforated record is placed on the spool supports, and the sheet attached to and wound by hand onto the take up roll 95 until the starting point is opposite the tracker ducts. The mechanism is now ready to start. The starting lever is turned in the usual manner. As soon as the pad 34 is released from engagement with the table rim 100 35, the table starts in the usual manner.

The movement of the handle 33 moves the contact making member 45 so as to cause it to contact with and ride upon the inclined contact member 46. See starting position 105 of Fig. 5. As soon as the members 45 and 46 contact with each other an electric circuit is set up as follows: From the battery by the wire X' to the contact making member 45, the contact member 46, the wire X² to the electro-magnet 18, from the electro-magnet 18 by the wire X³ to the terminal 110 the wire 111 to the negative side of the battery.

When the electro-magnet 18 is energized 115 the bellows 30 is exhausted as hereinbefore explained, causing the gear 15 to be placed in mesh with the take-up gear 13. Since the motor which revolves 15 had previously been set in operation, the sheet 50 starts 120 movement over the tracker 51.

Continued movement of the handle causes the contact making member 45 to pass beyond the contact 46 and spring down onto the contact 43. As the circuit is broken, the 125 magnet 18 is deenergized, the valve 20 closes, the air from 22 is exhausted via the bleed 25. This causes the valve 27 to fall opening the atmospheric port 28 and closing the suction port 29. The admission of air by 130

28 to the duct 30', and thence to the pneumatic 30 permits the spring 30" to expand the bellows 30. The lever 17 still maintains its position holding the gear 15 in mesh 5 with the gear 18 because of the projection 48 on the spring held lever 47.

As soon as the spring contact making member 45 contacts with the contact member 43 an electric circuit is set up as follows: From the positive side of the battery 10 by the wire X' to the contact making member 45, to the contact member 43 by the wire X" to the contact element 41, the arcuate contact control member 36 (during half of 15 each revolution of the table), the contact element 42 by the wire 101 to the terminal 102 which is connected to the synchronizer. It returns through the synchronizer to the terminal 110 and thence by the wire 111 to 20 the negative side of the battery.

The phonograph is stopped in the usual manner by the operation of the starting handle 33. When, however, the member 45 is moved away from the contact 43 it engages 25 the insulating member 55 which thereby prevents a premature starting again of the winding apparatus. This is illustrated in the right portion of Fig. 5. The automatic musical instrument may be 30 stopped by any suitable means such as a device, part of which is designated generally by 54, which causes the music to be rerolled and the lever 17 put to vertical position ready for the next selection.

35 While I have described my invention in connection with a synchronizer such as that disclosed in Patent No. 1,279,640, I desire to have it understood that it is not limited to such a device.

40 It is also to be understood that changes and modifications may be made without departing from the spirit of my invention and within the scope of the appended 105 claims.

45 What I claim is:

1. A means for synchronically starting the 50 operation of two automatic instruments having a synchronizer, said means comprising a hand controlled starting device, a connection between the hand controlled starting device and one of the instruments to start the same upon movement of the hand starting device and electric connections between the starting device and the other instrument 55 to start the same upon the same movement of the starting device.

2. A means for synchronically starting the 60 operation of two automatic instruments having a synchronizer, said means comprising electrical connections between the starting handle of the phonograph and the starting mechanism of the automatic instrument to operate the starting mechanisms of the automatic instrument when the starting handle 65 is moved to starting position.

3. A means for synchronically starting the 70 operation of two automatic instruments having a synchronizer, said means comprising a starting handle, connections between the starting handle and the instruments to start the two upon initial movement of the starting handle, and connections between the handle and the synchronizer and means for completing the connections by further movement of the starting handle. 75

4. A means for synchronically starting the 80 operation of two automatic instruments having a synchronizer, said means comprising a starting handle, connections between the starting handle and the instruments to start the two upon initial movement of the starting handle, electric connections between the handle and the synchronizer and means for completing the connections by further movement of the starting handle. 85

5. A means for synchronically starting the 90 operation of two automatic instruments having a synchronizer, said means comprising a starting handle having means for starting the phonograph, an electric contact member adjacent the starting handle a contact making member attached to the handle in position to engage the contact member when the handle is moved, electric connections between the handle and the starting mechanism of 95 the automatic instrument to operate the latter from the former, and connections between the handle and the synchronizer and means for preventing the connections to the starting mechanism and the synchronizer 100 being operative at the same time.

6. A means for synchronically starting the 105 operation of two automatic instruments having a synchronizer, said means comprising connections to the phonograph and the automatic instrument, an impulse causing device on the phonograph and in said connections, a starting handle having a connection with the phonograph to hold the table in operation in one position and permit it to operate 110 in another position, said handle also having connections with the starting mechanism of the automatic instrument and means attached to the handle to connect or disconnect the impulse causing device with the 115 synchronizer.

7. A means for synchronically starting the 120 operation of two automatic instruments having a synchronizer, said means comprising a starting handle having means for starting the phonograph connections between the starting handle and the driving means for the automatic instrument, said connections comprising electro pneumatic means controlled directly by the handle to start the 125 automatic instrument when the handle is moved.

8. A means for synchronically starting the 130 operation of two automatic instruments having a synchronizer, said means comprising

a starting handle having means for starting the phonograph, connections between the starting handle and the driving means for the automatic instrument said connections comprising an electro magnet under direct control of the handle, a valve controlled by the electro magnet, a bellows controlled by the valve and means connecting the bellows with the driving mechanism to start the latter when the handle is moved.

9. A means for synchronically starting the operation of two automatic instruments having a synchronizer, said means comprising a hand controlled starting device, connections between the starting device and the starting mechanisms of the respective instruments, switch means controlled by the starting device for operating the starting mechanisms upon an initial movement of the starting device and for completing the

connections of the synchronizer upon further movement of the starting device.

10. A means for synchronically starting the operation of two automatic instruments having a synchronizer, said means comprising a hand controlled starting device, connections between the starting device and the starting mechanisms of the respective instruments, switch means controlled by the starting device for operating the starting mechanisms upon an initial movement of the starting device and for disconnecting the starting mechanisms and completing the connections of the synchronizer upon further movement of the starting device. 30 35

In testimony whereof, I affix my signature.

GEO. W. GITTINS,
Administrator of the Estate of Heinrich Bockisch, Inventer, Deceased.
